UNITED STATES PATENT OFFICE.

CLEMENTE DEL GRANDE, OF ISERNIA, ITALY, ASSIGNOR TO CHARLES N. ROMAINE, OF PETERSBURG, VIRGINIA.

PYROTECHNIC.

SPECIFICATION forming part of Letters Patent No. 471,703, dated March 29, 1892.

Application filed December 4, 1891. Serial No. 413,999. (No model.)

To all whom it may concern:

Be it known that I, CLEMENTE DEL GRANDE, a subject of the King of Italy, and a resident of Isernia, in the Province of Campobasso,

5 Italy, but temporarily residing at Petersburg, in the county of Dinwiddie and State of Virginia, have invented a new and useful Improvement in Pyrotechnics, of which the following is a specification.

10 The object of my invention is to provide a novel article of fire-works, which on ignition will give a loud whistle or a colored flame succeeded by a series of detonations, which detonations or explosions may vary in loudness, if desired, and may be either with or without the ejection of stars, colored balls, or rockets; and my invention consists of a tube or core charged with a whistling or other pyrotechnic compound and secured in any suitable way to a handle, in combination with a series of bombs suspended from the tube and connected to the compound and to each other by a suitable fuse.

15 An article of this description is useful for pyrotechnic purposes in parades and celebrations, as well as for signaling purposes, where-in the loudness or nature of the whistle or flame and the succeeding detonations may be arranged in accordance with any predetermined code.

20 In the accompanying drawing, which illustrates my invention, A is a handle composed of wooden or other suitable material of any convenient length.

25 B is a tube or core of pasteboard, paper, or other suitable material charged with whistling or other pyrotechnic compound b—such, for example, as the whistling picrate of potash described in Letters Patent to Antonio

30 del Grande, No. 411,714, September 24, 1889.

b' is a fuse for igniting the compound.

35 The tube B is secured to the handle A in any suitable way. In the drawing it is shown as fastened by means of a wire or string a.

40 C C' are bombs connected in a series by the fuse c to the compound in the tube B and hanging freely from said tube.

D is a wrapper of strong paper or other suitable material surrounding said fuse c and serving to suspend the bombs from the tube 50 where a fuse is used, which entirely consumes when ignited.

E is a fancy wrapper, which may surround any or all of the various parts of the pyrotechnic, if desired. 55

In firing the fire-work it is held by the handle, and the fuse b' being ignited the compound burns with the production of a whistling noise or a colored flame, as the case may be, followed by the explosion of the bombs in 60 succession.

I thus provide an article of fire-works which permits of the use of loud and large bombs without jar to the hand of the person holding the handle, such as would result were the 65 bombs rigidly secured to the handle, against which part of their explosive force would then be exerted.

In the drawing I have shown the last bomb C' as much larger and consequently louder 70 than the others.

When operating the particular signal shown in the drawing, attention being first called by the colored flame or whistle from the tube, there will be five low explosions, which may 75 be, if desired, at fixed intervals, (according to the length of the fuse,) terminating in a loud report; but I do not limit myself thereto, as the bombs may all be of equal loudness or varied in number or loudness, or both, 80 in accordance with any predetermined or well-known code for signaling purposes, as already stated. Neither do I limit myself to any particular compound or any particular means of connecting the whistling-tube to the 85 handle, or of suspending the bombs from the tube, as they may all be greatly varied without departing from the spirit of my invention.

Having thus described my invention, what 90 I claim as new, and desire to secure by Letters Patent, is—

An article of pyrotechnics, consisting of a handle, a tube packed with a whistling or

other compound and secured to one end of | my hand in the presence of the subscribing
said handle, a fuse for igniting said com-
pound, and a series of bombs connected to
each other and to the compound in the tube
5 by a fuse and freely suspended by one end
from said tube and handle, substantially as
described.

In testimony whereof I have hereunto set

my hand in the presence of the subscribing
witnesses.

CLEMENTE DEL GRANDE.
